CLAIM

The ornamental design for a container for defibrillator pads, as shown and described.

DESCRIPTION

FIG. 1 is a top perspective view of the container for defibrillator pads.

FIG. 2 is a left side view of the container for defibrillator pads of FIG. 1.

FIG. 3 is a right side view of the container for defibrillator pads of FIG. 1.

FIG. 4 is a front view of the container for defibrillator pads of FIG. 1.

FIG. 5 is a rear view of the container for defibrillator pads of FIG. 1.

FIG. 6 is a top view of the container for defibrillator pads of FIG. 1; and,

FIG. 7 is a bottom view of the container for defibrillator pads of FIG. 1.

The portions of the container for defibrillator pads shown in broken lines form no part of the claimed design.

1 Claim, 3 Drawing Sheets

Related U.S. Application Data

continuation of application No. 15/046,778, filed on Feb. 18, 2016, now Pat. No. 9,533,139, which is a division of application No. 14/458,090, filed on Aug. 12, 2014, now Pat. No. 9,289,590.
